UNITED STATES PATENT OFFICE.

ROY J. ROBERTSON, OF NEW YORK, N. Y.

CARBURETER.

1,184,878

Specification of Letters Patent. Patented May 16, 1916.

Application filed June 3, 1916. Serial No. 843,199.

To all whom it may concern:

I, Roy J. Robertson, a citizen of the United States, and a resident of the city of New York, borough of Brooklyn, county of Kings, and State of New York, have invented a new and Improved Carbureter, of which the following is a full, clear, and exact description.

This invention relates to improvements in carbureters, and has for an object to provide an improved structure wherein the air and fuel may mix properly before leaving the carbureter.

Another object of the invention is to provide a carbureter which presents a double supply of fuel in a finely divided condition when the carbureter is being used for high speed and a single supply when the carbureter is used for low speed, whereby the richness of the mixture is maintained substantially even throughout.

In carrying out the objects of the invention an adjustable diaphragm of any suitable kind is provided as a throttle, the same, however, being formed preferably adjustable toward and from the center. This throttle contacts with a specially constructed nozzle designed to permit the discharge of fuel from one set of openings when the throttle is almost closed and permits the discharge of fuel from a second discharge passageway as well as the first when the throttle is open. This fuel discharge member or nozzle is connected with a supply tank provided with a float of any desired kind.

In the accompanying drawings Figure 1 is a longitudinal vertical section through a carbureter embodying the invention; Fig. 2 is a longitudinal vertical section through the discharge nozzle of the carbureter shown in Fig. 1, the same being shown on an enlarged scale; Fig. 3 is a section through Fig. 2 on line 3--3.

Referring to the accompanying drawings by number, 1 indicates a housing of any desired kind provided with a jacket 2 which may receive a warming fluid if desired. It is desirable to provide this warming fluid so as to allow a better mixing of the fuel and the air as the evaporation of the fluid naturally causes a chilling effect. The results are better if the explosive mixture can enter the engine at an atmospheric temperature or warmer instead of cooler as would be the case unless means were pro-

vided as just described. Arranged in the casing or housing 1 is a throat 3 through which the air and fuel are passed, and from thence into the engine. The throat 3 merges into a passageway 4, which in turn merges into an air inlet 5. Preferably arranged in the air inlet 5 is a sleeve 6 which may be held in place in any desired manner, and which produces a restricted opening or passageway for the air. Arranged above the sleeve 6 is a throttle 7 opening from and closing toward the center, which throttle is operated by a lever 8 so as to be opened and closed for varying the amount of air passing from the inlet 5 to the throat 3.

Arranged in the passageway 4 is a fuel discharge member or nozzle 9 which is arranged so as to discharge fuel out of one set of openings when the engine is running slow and out of two sets of openings when the engine is running at higher speeds. As clearly shown in Fig. 2 the discharge member 9 is formed with a tubular outer section 10, a tubular inner section 11 and a spray member 12 having a tubular extension 13 projecting into tubular section 11. The upper end of the tubular section 11 is provided with a flaring member 14 designed to break up the fuel passing out of the tubular section 10, whereby the same may be more easily commingled with the air. It will be observed that the nozzle 9 is provided with a shoulder 15 against which the air and fuel strike whereby the fuel is again broken up or pulverized, as it were. This breaking up into small particles causes the air to more readily absorb the fuel even though the same may be a comparatively heavy oil, as for instance kerosene. The spray 12 is provided with an annular groove 16 from which extends a plurality of passageways 17 merging into a single passageway 18, which passageway registers with the opening or passageway in the tubular extension 13, whereby the apertures 17 receive fuel from the interior of the tubular section 11. The tubular section 11 is provided with a valve seat 19 co-acting with the valve 20, which valve is threaded at 21 into the lower part of the tubular section 11, which is likewise threaded for receiving the threaded portion 21. The interior surface of the tubular section 11 at the bottom is provided with threads 22 which allow the section 11 to be threaded into the threaded portion

23 of casing 1, and also to receive the packing boxes 24 and 25 and the lock nut 26. The lower end 27 of the valve 20 is preferably provided with a polygonal head so that the valve may be adjusted as desired. It will be noted that a plurality of radial apertures 28 are provided in section 11 near the seat 19 so that fuel may pass from the interior of tubular section 10 into the interior of tubular section 11, the valve 20, of course, controlling the flow of fluid. The tubular section 10 receives the fuel from a feed passageway 29 connected with the supply tank 30. A suitable valve 31 is provided in passageway 29 so as to entirely shut off the passageway whenever desired, or adjust the amount of fuel entering nozzle 9. The supply tank 30 is provided with a float 32 which may be of any desired structure.

In operation when it is desired to use the carburetor valve 31 is opened and the fluid from tank 30 which is supplied from any suitable source rises in the discharge member 9 to the same level as that in the tank, namely, near the upper end of the tube or section 10. The lever 8 is then operated for moving the throttle 7 in substantially the positions shown in Fig. 1. The engine is then turned over in the usual manner and in turning over will draw in air through opening 5, which air will pass between the nozzle 9 and the throttle. By reason of the closeness of the throttle 7 to the nozzle 9, the air will draw in fuel only through the aperture 17. It will be observed that the fuel in the space 44 will be drawn out and mixed with the first air that passes into the engine, and will by reason of the quantity provide an extremely rich mixture, thus allowing the engine to start immediately even if previously starved. After the engine has started the same will draw air and fuel through aperture 17 and also through the passageways or openings in member 14, the air passing downwardly between member 10 and member 11 and then through aperture 28 where it mixes with the fuel as it passes out as just mentioned. As the engine begins to move the throttle 7 is opened wider and wider according to the speed desired. As soon as the throttle begins to open the fuel will begin to flow from the tubular section 10 so that on an increase of air there will be increase of fuel supplied. It will thus be seen that at low speed fuel is drawn through the spraying head 12, while at high speed, fuel is drawn through openings at different heights, namely, through head 12 and member 10. The fuel is broken up into a spray by the various annular projections on the nozzle 9 so that different kinds of fuel may be used, as for instance, gasoline or even kerosene with equally good results. By providing a

proper mixing of the broken up or sprayed fuel with the air a proper explosive mixture is produced which will give no smoke or very little. In order to adjust the opening between tubular section 10 and member 14, which member acts as a valve, the tubular member 11 is threaded at 23 whereby the same may be readily adjusted. It is evident that this adjustment is not very great and consequently the movement of the nozzle 9 will not be appreciable with respect to the throttle 7. In connection with the adjustment of these various parts it is to be noted that by positioning the throttle valve 7 as shown in Fig. 1 there is provided only one expansion chamber both for the air and fuel. This expansion chamber is within the carburetor and opposite the warming jacket 2, whereby the explosive mixture passes into the engine in the most satisfactory condition.

What I claim is:

1. In a carburetor of the class described, a casing, a spraying device arranged in said casing, said spraying device comprising a tubular member, in communication with a source of gasoline supply, a second tubular member arranged in said first mentioned tubular member and spaced therefrom, said second mentioned tubular member having apertures extending therethrough, a valve arranged in said second mentioned tubular member for shutting off the supply of fuel passing through said apertures, and a spraying nozzle connected with said second mentioned tubular member for spraying the fuel fed thereto, said spraying nozzle having its discharge apertures at a higher point than said first mentioned tubular member, whereby fuel will be drawn from the spraying member when the carburetor is operating at slow speed, and fuel will be drawn from the spraying member and said first mentioned tubular member when the carburetor is operating at high speed, and a throttle valve co-acting with said spraying device for regulating the air and fuel.

2. In a carburetor of the class described, a casing, a throttle valve arranged in said casing, a spraying device arranged in said casing with the upper end adjacent said throttle valve whereby the volume of air permitted to pass the spraying device is controlled by said throttle valve, said spraying device comprising an outer tubular member, an inner tubular member, a spraying nozzle mounted in said inner tubular member and extending above said inner tubular member and above said outer tubular member, said spraying nozzle being provided with passageways between the nozzle and said inner tubular member whereby there will be provided a communication between the interior of said inner tubular member and the exterior of the spraying device.

device, said inner tubular member having an aperture adjacent the lower end thereof, and a valve arranged to engage the seat above said opening whereby the air from the interior of said outer tubular member and the fuel are controlled simultaneously.

3. In a carbureter of the character described, a casing, a throttle valve arranged in said casing, a spray device arranged in 10 said casing with the upper end adjacent said throttle valve, and means for supplying fuel oil to said spray device, said spray device comprising an outer tubular member open at the top and bottom, a feed member connected to the lower end of said outer tubular member for feeding oil thereto, an inner tubular member connected with said feed member adjacent the lower end, said inner tubular member being provided with 15 apertures adjacent the lower member for the admission of fuel, and a valve seat through which said fuel is arranged to pass, said inner tubular member at the upper end being also formed with a cone-shaped structure for guiding the fuel from the outer tubular member at an angle as the same is 20 25

discharged, a valve member adapted to be moved toward and from said seat for controlling the flow of oil into said inner tubular member, and a spray nozzle mounted on 30 said inner tubular member with the upper part spaced therefrom, said spray nozzle being provided with slots or openings whereby oil may pass from said inner tubular member to a position beneath said spray 35 nozzle, said spray nozzle being provided with an extension projecting an appreciable distance into said inner tubular member, said spray device being also provided with a passageway extending through said extension and to the periphery of the upper part of said spray nozzle, whereby a plurality of points of discharge are provided, said points of discharge being at different levels.

In testimony whereof I have signed my 45 name to this specification in the presence of two subscribing witnesses.

ROY J. ROBERTSON.
